UNITED STATES PATENT OFFICE.

JOHN HEWITSON, OF TAUNTON, MASSACHUSETTS, ASSIGNOR TO REED & BARTON, OF SAME PLACE.

DESIGN FOR ORNAMENTING METAL SURFACES.

SPECIFICATION forming part of Design No. 11,658, dated February 24, 1880.

Application filed January 3, 1880. Term of patent 7 years.

To all whom it may concern:

Be it known that I, JOHN HEWITSON, of Taunton, in the county of Bristol and State of Massachusetts, have originated a new Design 5 for Ornamenting Metal Surfaces; and I do hereby declare the following to be a full, clear, and exact description of the same.

In the accompanying photographic illustration are represented a silver cup, whose surface at *a* is ornamented by my improved design, and a flat piece of metal, *b*, correspondingly ornamented. The finish is formed mechanically of a series of closely-joined irregular patches of parallel indentations, as better illustrated in the hand-drawing at *c*, the lines of one patch or series being arranged at a different angle to that of the lines of the adjacent patches, so that the reflected light strikes the eye with the mottled appearance of snow flakes.

As the sheen of a bright metallic surface is

necessary to give a perfect illustration of the finish, the hand-drawing can therefore only illustrate the mechanical structure of the surface which, with the metals, gives the beautiful frosted or snow-flake appearance, which constitutes my design, and the effect of which is best illustrated in the photographic illustration. 25

Having thus described my invention, what 30 I claim is—

A design for metal surfaces composed of a conjoined series of irregular patches of parallel indentations, with the parallel indentations of one patch arranged at a different angle to the adjacent parallel indentations, substantially as described. 35

JOHN HEWITSON.
